UNITED STATES PATENT OFFICE.

JOSEPH S. RINSCHLER, JR., OF NEW YORK, N. Y.

DESIGN FOR A JAR.

56,710.

Specification for Design.

Patented Nov. 30, 1920.

Application filed October 13, 1919. Serial No. 330,320 $\frac{1}{2}$. Term of patent 14 years.

To all whom it may concern:

Be it known that I, JOSEPH S. RINSCHLER, Jr., citizen of the United States, and resident of New York city, in the county of New York and State of New York, have invented a new, original, and ornamental Design for a Jar, of which the following is a specification.

Referring to the figures, showing my design—

Figure 1 is an elevation of an ornamentally designed jar cover.

Fig. 2 represents a section of the same taken on line 2—2 of Fig. 3.

Fig. 3 is a bottom view of the jar cover.

Fig. 4 is a plan view of the covered jar.

Fig. 5 is a sectional view of the covered jar taken on line 5—5 of Fig. 4.

Fig. 6 is an elevation of the covered jar, representing the complete combination of my design.

Particular attention is called to the ornamental effect obtained through the combination of the fancy cover design together with the peculiar jar shape.

The former being visible, the covered jar gives an impression of an artistically formed chimney design.

It is understood that Figs. 1, 2, and 3 are illustrated for the sole purpose of making it clear how the combined effect of my design, shown in Figs. 4, 5 and 6, is produced.

No claim is made for the jar-cover alone or the jar without the cover.

What I claim is:—

The ornamental design for a jar, as shown.

Signed at New York city, in the county of New York, and State of New York, this 11th day of October, A. D. 1919.

JOSEPH S. RINSCHLER, JR.
